UNITED STATES PATENT OFFICE.

CHARLES F. CLAWSON, OF MOUNT PLEASANT, IOWA, ASSIGNOR OF ONE-FOURTH TO JOHN C. BAKER AND ONE-FOURTH TO OTTO A. GEESEKA, OF MOUNT PLEASANT, IOWA.

RAILWAY-TRACK APPLIANCE.

No. 828,929.

Specification of Letters Patent.

Patented Aug. 21, 1906.

Application filed September 5, 1905. Serial No. 277,082.

To all whom it may concern:

Be it known that I, CHARLES F. CLAWSON, a citizen of the United States, residing at Mount Pleasant, in the county of Henry and State of Iowa, have invented certain new and useful Improvements in Railway-Track Appliances, of which the following is a specification.

My invention relates to improvements in railway-track construction, having for its general object to increase the safety and comfort of railway travel.

To this end my invention resides in a novel track appliance which in operation combines a considerable number and variety of useful functions, among which may be mentioned the prevention of the "creeping" of the rails, the lateral bracing and elastic support of the rail-joints, the prevention of the spreading and tipping of the rails, and the deadening of the noise and pounding of the rails in passing over the joints.

A device embodying the principle of my invention is illustrated in the accompanying drawings, in which—

Figure 1 is a perspective view of a portion of a railway-track, showing the device of my invention applied to one of the rail-joints thereof; and Fig. 2 is a cross-sectional view on the line 2 of Fig. 1.

Referring to the drawings, 5 may designate the ties, and 6 the meeting ends of two rails of the railway-track. These rails are shown as meeting upon one of the ties.

7 designates the fish-plates, which may be of any usual or approved form, but which as herein shown are of that type having a longitudinal outwardly-projecting rib 6^a on their upper margins. The fish-plates hug the webs of the rails snugly, being secured thereto by the usual bolts 7^a and nuts 8.

9 designates as an entirety the improved device forming the subject-matter of my present invention. This may comprise a substantially flat base-plate 9^a, adapted to overlie the base of the rail and the upper surface of the tie, being provided with spike-holes, by which it is secured directly to the tie and rail-base through spikes 10. The upstanding portion 9^b of this member has substantially the form of half a hollow cylinder or roll, disposed with its axis parallel with the rails and of a height to snugly fit at its

upper edge beneath the rib of the fish-plate. The member 9^b is preferably made of a length 55 just sufficient to fit between the heads or nuts of adjacent tie-bolts, by reason of which it possesses the function of a bolt or nut-lock for these bolts.

The device described is preferably applied to both sides of the rail at the joint, as shown in Fig. 2, in which position it serves a variety of functions. In the first place, being securely spiked to the tie and engaging the bolts of the joint at both sides, it strongly resists any creeping tendency of the rails. Again, being made of spring-steel, the roll-like form of the upright member constitutes an elastic support for the meeting ends of the rails through the rib of the fish-plate, preventing pounding of the rails under the impact of the wheels in passing over the joints, deadening the usual noise accompanying the passage of the wheels over the joint and causing both ends of the rails, to the extent 75 that they do yield under the weight of the strain, to yield simultaneously and to an equal extent, thus producing substantially the effect of a continuous or unbroken rail. The two upstanding members being slightly 80 inclined toward each other, as shown, the downward pressure naturally tends to cause these members to spring toward each other, whereby the device serves the further function of a rail-clamp, while the outer members 85 on each side of the track also constitute braces to prevent spreading and tipping or overturning of the rails. It will also be seen that aside from clamping the rails and thus securing their perfect alinement the device of 90 the present invention also securely clamps the fish-plates against the rails, thus reinforcing the action of the clamping-bolts and serving the function of the latter should they become loose.

The base member of the device may be of any suitable form; but I prefer the broad or wide dovetailed form herein shown, as it affords a secure hold upon the tie and a maximum resistance to lateral strains. Furthermore, by overlying the bases of both rails at the joint and clamping said bases against the face of the tie it prevents the rise of one rail end relatively to the other, as well as the depression of one end relatively to the other.

I am aware that rail-braces having a base adapted to be spiked to the tie and an inclined strut bearing against the outer side of the rail web and head are old; but, so far as I am aware, the present invention presents the first application to a rail-joint of a device having the elastic character and possessing the variety of functions hereinabove described.

10. While I have shown the device as applied to a rail-joint, it is evident that it may be usefully applied as a brace to an intermediate portion of the rail.

I claim—

15. 1. A track appliance comprising an integral member having a substantially flat base adapted to be secured to a tie and a body portion in the form of a horizontally-disposed transversely elastic half-roll adapted and positioned to receive downthrusts through the head of the rail and free to yield under a weight imposed on the rail, substantially as described.

20. 2. A track appliance comprising an integral member having a broad substantially flat base adapted to be spiked to a tie, and an exteriorly-rounded body the upper horizontal margin whereof is adapted to underlie the rib of the rail-clamp at a rail-joint, substantially as described.

25. 3. The combination with the meeting ends of a pair of rails, a tie on which said rail ends rest, and a ribbed fish-plate overlapping said

rail ends, of a rail-brace having a base portion secured to the tie and a transversely elastic body portion abutting against said fish-plate beneath and in contact with the rib of the latter, substantially as described.

4. The combination with the meeting ends of a pair of rails, a tie on which said rail ends rest, and a ribbed fish-plate overlapping said rail ends, of a rail-brace having a broad substantially flat base portion secured to the tie, and a body portion in the form of a half-roll abutting against said fish-plate beneath the rib of the latter, substantially as described.

5. A rail-joint brace made of elastic material and comprising a broad substantially flat base portion adapted to be secured to the face of the tie and overlie the rail-base, and a body portion in the form of a half-roll adapted to fit beneath the longitudinal rib of the fish-plate, substantially as described.

6. An integral or one-piece steel rail-joint brace comprising a substantially flat outwardly-flaring base portion adapted to be secured to the face of the tie and overlie the rail-base, and a body portion in the form of a horizontal half-roll adapted to fit beneath and elastically support the longitudinal rib of the fish-plate, substantially as described.
